UNITED STATES PATENT OFFICE

EDWARD L. BRONSTIEN, OF ST. PAUL, MINNESOTA

SPRING MECHANISM

Application filed August 2, 1929. Serial No. 383,088.

The present invention relates to an attachment for a spring compressing and feeding machine.

In the manufacture of upholstery and spring filled mattresses it is common practice to enclose a plurality of coil springs in small, individual cloth containers.

At present, it is customary to manually compress these springs and insert them in an opening between two tongues, the tongues being then inserted in the cloth pockets in which the coils are to be enclosed.

An object of the present invention is to mechanically compress a coil spring and to insert it in a cloth pocket.

In order to attain this object, there is provided, in accordance with one feature of the invention, a pivoted lever which receives the spring when discharged from the spring, forming machine and drives the spring forward between two cam surfaces to compress the spring, each spring as it is moved forward between the cam surfaces acting upon the previously compressed spring to force it forward into a cloth pocket positioned to receive it.

These and other features of the invention will be more fully brought out in the following description and the accompanying drawings, in which:

Figure 1 is a view in top elevation of the attachment.

Figure 2 is a view in side elevation thereof.

Figure 3 is a view in front elevation thereof; and

Figure 4 is a view in side elevation of a cam and lever arrangement which operates the attachment on the completion of each cycle of operation of the spring making machine.

Referring to the drawings in detail, it is not deemed necessary to show the spring forming machine, as these machines are well known to the art, the device being adaptable for use in connection with any machine which automatically forms and discharges coil springs. The point of discharge of the coil springs from the forming machine is indicated at 1, a curved guide member 2 being mounted to be positioned centrally of the

spring as it is discharged, to receive the spring and guide it downwardly over a receiving arm 3. The receiving arm is purposely placed out of alignment with the guide arm 2 so that when the spring 4 is dropped over the arm 3, its upward rebound will be checked by striking the lower surface 5 of the guide arm 2. The spring drops onto a lower camway 6, which comprises a pair of curved plates sloped upwardly and forwardly. The lever arm 3 is pivotally connected to a second lever 7 which is fixedly secured to a shaft 8, which in turn is pivotally mounted upon the frame 9 of the attachment.

An operating lever 10 is fixedly secured to an end of the shaft 8 and the upper end of this lever is pivotally secured to a rod 11 which extends rearwardly, the other end thereof being secured to an operating lever 12. A turnbuckle 13 is provided centrally of the rod 11 to adjust the length thereof. The operating lever 10 is provided with a cam roller 13 which rides against a cam surface 14 on a sprocket 15, which rotates once for each cycle of operation of the spring making machine. This cam is positioned to operate the lever 10 as each spring is discharged from the forming machine. Upon the completion of each cycle of operation of the spring forming machine, the cam 14 forces the operating lever forward, moving the lower lever 7 and with it the upper lever 3, forward to drive the spring 4 forward between the upper and lower cam surfaces to compress the spring.

The lever 3 is fixedly mounted on a shaft 16 which is pivotally mounted in the lever 7. A set screw 18 is mounted in the lower lever 7 to rest against the rear surface of the lever 3 to limit the rearward pivotal movement thereof. A locknut 19 is provided to lock the screw 18 in an adjusted position.

The upper cam surface comprises a pair of curved metal plates 20 and 21, which converge toward the lower camway 6 so that at their upper and forward ends they are separated a distance which is determined by the required degree of compression which it is desired to give the springs 22 when inserted in the pockets. A pair of guide

tongues 23 and 24 are mounted forwardly of the upper and forward ends of the camway and are spaced apart the same distance as the upper and forward ends of the camway, so that the spring may be slidably moved forward between these tongues, while still held in the required degree of compression. A pawl 25 is pivotally mounted near the upper end of the upper camway and is provided with teeth 26 in the lower surface thereof to engage the springs 22 and prevent their being retracted when the lever 3 is returned to a normal position. The pawl 26 is provided with a transverse pin 27 which rests upon the upper surface of the upper cams 20 and 21 to limit the downward movement of the pawl and prevent it from dropping into the opening in the center of the coil springs. The pawl is constantly forced downwardly by means of a spring mounted in spring drums 33 having tension adjustment as at 34.

The operation of the device is as follows:

As the coil spring 4 is completed it is severed by the forming machine in a well known manner and is guided by the guide arm 2 downwardly and falls onto the upper lever arm 3 to rest upon the lower camway 6. As it is dropped onto the camway it rebounds and strikes the end 5 of the guide arm 2 which prevents it from rebounding upwardly with the possibility of striking the end of the upper camway when it is forced forward. After the spring is dropped onto the lever arm 3, the cam 14 engages the cam roller 13 mounted upon the operating lever 12 forcing the operating lever 12 forward. This drives the rod 11 forward and swings the lever 10 and with it the lever 7 forward, forcing the coil spring between the camways 6 and 20, the levers 7 and 3, moving forward to the dotted line position 3a, shown in Figure 2. The spring which was moved forward by the previous operation of the machine occupies the position X in Figure 2 until the time when the next spring is moved forward by the lever arm 3. Each succeeding spring forces the operating spring from the position X to the position Y between the tongues 23 and 24 in Figure 2. As the cam 14 rotates, the cam roller 13 passes the high point on the cam and the retracting spring 28 then moves the operating lever 10 rearwardly, drawing the thrust rod 11 rearwardly and permitting the lever 7 and the lever 3 to return to normal. As the lever 3 is drawn rearwardly, the pawl 25 holds the spring into position X and the lever 3 then pivots upon the rod 16 to the dotted line position 3b in Figure 2, withdrawing the lever arm 3 from the spring. As soon as the lever arm clears the spring it is returned to its normal position resting against the screw 18 by means of the spring 29 which engages the lever 30 on the end of the rod 11 upon which the lever 3 is mounted.

The pocketed cloth strip 35 for receiving the springs is shown in Figure 1, and comprises a strip of cloth folded lengthwise upon itself, as at 31, and sewed transversely by single rows of stitching, as at 32. At each spring is inserted in a pocket in this strip, the strip is manually withdrawn with the spring in the pocket and the next pocket in the strip is inserted over the tongues 23 and 24 to receive the next successive spring as it is discharged.

I claim:

1. A spring machine attachment, comprising a frame adapted to be attached to a spring manufacturing machine, a lever pivotally mounted on said frame, a second lever pivotally connected to said first lever and adapted to receive a coil spring as it is discharged from said spring manufacturing machine, a camway mounted in the path of said second lever as it is moved forward to laterally compress the coil spring carried by said second lever, operative means connecting said levers to said spring manufacturing mechanism to move said levers forward on completion of each cycle of operation of said spring manufacturing machine, and means to withdraw said second lever from engagement with said spring on a retractive movement of said levers.

2. A spring machine attachment, comprising a frame adapted to be attached to a spring manufacturing machine, a lever having a hinged plate intermediately thereof, pivotally mounted on said frame, means mounted to normally hold the parts of said lever in alinement with each other, means operatively connecting the lever to said spring machine to move said lever forward upon the completion of each cycle of operation of said spring manufacturing machine, cam means mounted to laterally compress said spring as it is moved forward by said lever, and a pawl mounted to engage said spring at the full forward movement of said spring by said lever to prevent retraction of said spring.

3. A spring machine attachment comprising a frame adapted to be attached to a spring forming machine, a post mounted centrally of the spring-forming mechanism and of smaller diameter than the coil spring formed by said mechanism, a lever arm normally in alinement with one side of said post and out of alinement with another side of said post, a plate mounted to arrest downward movement of springs discharged from said coiling mechanism at a predetermined point, said plate being positioned at an angle to direct springs falling thereon upwardly against the portion of said post not in alinement with said lever, means having operative connection with said coiling mechanism to move said lever forward upon the completion of each spring, and a camway mounted

to compress said spring on a forward movement of said lever.

4. A spring machine attachment comprising a frame adapted to be attached to a spring forming machine, guide means mounted to lie within a coil spring during its formation, a lever mounted to receive a coil spring as it is discharged from said guide means, a plate mounted to arrest the downward movement of said coil spring at a predetermined point, said guide means being offset from said lever to arrest the upward rebound of a coil spring after striking said plate, means mounted to move said lever forward after the completion of each spring, and a camway mounted to compress said coil spring during a forward movement of said lever.

5. A spring machine attachment comprising a frame adapted to be attached to a spring forming machine, guide means mounted to lie within a coil spring during its formation, a lever mounted to receive a coil spring as it is discharged from said guide means, a plate mounted to arrest the downward movement of said coil spring at a predetermined point, said guide means being offset from said lever to arrest the upward rebound of a coil spring after striking said plate, means mounted to move said lever forward after the completion of each spring, a camway mounted to compress said coil spring during a forward movement of said lever, and means mounted to grip said coil spring when compressed to prevent a retractive movement thereof.

6. A spring machine attachment comprising a frame adapted to be attached to a spring forming machine, guide means mounted to lie within a coil spring during its formation, a lever mounted to receive a coil spring as it is discharged from said guide means, a plate mounted to arrest the downward movement of said coil spring at a predetermined point, said guide means being offset from said lever to arrest the upward rebound of a coil spring after striking said plate, means mounted to move said lever forward after the completion of each spring, a camway mounted to compress said coil spring during a forward movement of said lever, means mounted to grip said coil spring when compressed to prevent a retractive movement thereof, and means to withdraw said lever from said spring in a fully compressed condition at the completion of each cycle of operation thereof.

7. A spring machine attachment, comprising a frame adapted to be attached to a spring manufacturing machine, a lever pivotally mounted on said frame, lever operating means coordinating with said spring manufacturing machine to reciprocally move said lever forward and back upon the completion of a spring by said spring manufacturing machine, a cam-way mounted in the path of

said lever as it is moved forward to laterally compress a coil spring carried by said lever, and means mounted to withdraw said lever from engagement with said spring on a retractive movement of said lever.

8. In an apparatus for compressing coil springs, the combination of a throat having converging walls between which the springs may be received and which serve to compress the springs axially when the latter are moved along the throat toward the converged ends of said throat walls, a reciprocating finger adapted to enter the coils of said springs and move the latter along said throat, and means for preventing retrograde movement of said springs when the rear portions of said springs are engaged by said reciprocating member in its retractive movement.

9. In an apparatus for compressing coil springs, the combination of a throat having converging walls between which the springs may be received and which serve to compress the springs axially when the latter are moved along the throat toward the converged ends of said throat walls, a reciprocating finger adapted to enter the coils of said springs and move the latter along said throat, and means for automatically disengaging said finger from the springs subsequent to the forward movement of the latter in said throat.

10. In an apparatus for compressing coil springs, the combination of a throat having converging walls between which the springs may be received and which serve to compress the springs axially when the latter are moved along the throat toward the converged ends of said throat walls, and a reciprocating finger adapted to enter the coils of said springs and move the latter along said throat, said throat being provided with a shoulder facing its discharge and to prevent retrograde movement of the springs after passing said shoulder.

11. In an apparatus for compressing coiled wire springs, the combination of a throat having converging walls, an arm, means for reciprocating said arm in and along said throat so as to propel a coiled wire spring through said throat and thereby compress said spring axially, and spring feeding means synchronized with said arm operating means for delivering springs singly and successively to a position adjacent the intake end of said throat, so as to be engaged by said arm when the latter moves along said throat.

12. In an apparatus for compressing coiled wire springs, the combination of a throat having converging walls, an arm, means for reciprocating said arm in and along said throat so as to propel a coiled wire spring through said throat and thereby compress said spring axially, and spring feeding means synchronized with said arm operating means for delivering springs singly and successively to a position adjacent the intake end of

said throat, so as to be engaged by said arm when the latter moves along said throat, the arrangement including means for automatically disengaging said arm from said spring 6 after the completion of the forward movement of said arm.

13. In an apparatus for compressing coiled wire springs, the combination of a throat having converging walls, a rocking lever, 10 means for rocking said lever in and along said throat so as to propel a coiled wire spring through said throat and thereby compress said spring axially, spring feeding means synchronized with said lever operating means 15 for delivering springs singly and successively in timed relation to a position so that they will surround the free outer end of said lever, and means for automatically withdrawing the end of said lever from the interior of the 20 spring after the completion of the forward movement of the lever.

14. In an apparatus for compressing coiled wire springs, the combination of a throat having converging walls, a rocking lever, 25 means for rocking said lever in and along said throat so as to propel a coiled wire spring through said throat and thereby compress said spring axially, spring feeding means synchronized with said lever operating means 30 for delivering springs singly and successively in timed relation to a position so that they will surround the free outer end of said lever, and means for automatically withdrawing the end of said lever from the 35 interior of the spring after the completion of the forward movement of the lever, said last named means comprising a joint in said lever and means for rendering said joint effective during only the backward movement of said 40 lever.

In testimony whereof I affix my signature.
EDWARD L. BRONSTIEN.
